UNITED STATES PATENT OFFICE.

SLAYDON MURPHY, OF WESTONIA, MISSISSIPPI.

JOURNAL-BOX.

No. 844,887.

Specification of Letters Patent.

Patented Feb. 19, 1907.

Application filed October 2, 1906. Serial No. 337,092.

To all whom it may concern:

Be it known that I, SLAYDON MURPHY, a citizen of the United States, residing at Westonia, in the county of Hancock and State of Mississippi, have invented certain new and useful Improvements in Journal-Boxes; and I do hereby declare the following to be a full, clear, and exact description of the invention, such as will enable others skilled in the art to 10 which it appertains to make and use the same.

My invention relates to improvements in journal-boxes for railway-car trucks.

It has for its object to provide means 15 whereby the axle may be removed from the box without taking the box off the truck.

To this end the invention consists in providing an opening or doorway in the side of the box through which the end of the axle in 20 said box may pass. The invention comprises means to close said opening or doorway and the other features of construction and combinations of parts hereinafter described, and more particularly pointed out in 25 the claims concluding this specification.

In the accompanying drawings, illustrating the preferred embodiment of my invention, Figure 1 is a side view of a journal-box made in accordance with my invention, 30 showing the opening for removing the axle closed. Fig. 2 is a similar view with the door in the side open. Fig. 3 is a central vertical cross-sectional view of the box, showing the form and arrangement of the brass; and Fig. 35 4 is a central vertical longitudinal sectional view of said box.

Referring more particularly to the drawings, 1 represents the journal-box, adapted to be secured to the frame of a truck by the 40 bolts 2 2¹, one arranged at either side of said box and passing through eyepieces 3, secured thereto. One side of the box is provided with an opening 4 of proper length and width to permit the end of the axle 5, arranged in 45 the box, to pass therethrough. Said opening is closed by a door 6, adapted to neatly fit the same, said door being mounted on suitable hinges 7, preferably arranged at its lower edge. Eyepieces or loops 8 are secured 50 to the door in line with the eyepieces 3 on that side of the box, whereby the bolt 2 will pass through all of said eyepieces and hold the door shut. As an additional means of locking the door I have provided a locking-

pin 9, engaging another series of eyepieces or 55 loops 10, two of which are secured to the side of the box near its rear end and the other two of which are arranged in line therewith, but fastened to the door. Thus the door or closure is locked near both ends. 60

To remove the axle from the box, the bolt 2 is taken out, as is also the locking-pin 9. The door then being released is swung down on its hinges and the axles may be removed. It will be noted that it will be 65 very much easier and quicker to remove a pair of car-wheels when my invention is used than when the ordinary box without any opening in the side is employed.

To prevent the brass or bearing 11 in the 70 upper portion of the box from dropping down when the axle is removed, I mount said brass upon ledges 12 along the inner sides of said box. Said ledges are preferably provided with abutments 13 at the inner ends thereof to limit the inward movement of said brass. The upper portion and sides of the brass and the interior of the box above the ledge 12 form, approximately, five 75 sides of an octagon, as shown in Fig. 3. The 80 dust-board is made in two pieces. The upper half 14 extends through a slot 15 in the top of the box, and the lower half 14^a extends through a slot 15^a in the bottom of the box and is supported by a pin 16. 85

I claim—

1. A journal-box, for railway-car trucks, having an opening in its side through which the axle is adapted to pass, a hinged closure for said opening and means to lock said closure shut. 90

2. A journal-box, for railway-car trucks, having an opening in its side through which the axle is adapted to pass, a closure for said opening, a brass in the top of said box and 95 means to retain said brass in position when the axle is removed.

3. A journal-box, for railway-car trucks, having an opening in its side through which the axle is adapted to pass, a closure for said 100 opening, having eyepieces secured thereto, there being other eyepieces carried by the box and arranged in line with those on the closure, and a pin adapted to engage said eyepieces. 105

4. A journal-box of the character described, having an opening in its side through which the axle is adapted to pass, a closure

for said opening having two sets of eyepieces secured thereto, there being other eyepieces carried by the box and some arranged in line with each of the sets of eyepieces on the closure, a locking-pin adapted to engage some of the eyepieces on the box and one set thereof on the closure, and a bolt for securing the box to the frame of the truck, said bolt

engaging the other eyepieces on the box and the other set thereof on the closure.

In testimony whereof I affix my signature in presence of two witnesses.

SLAYDON MURPHY.
